BENDING APPARATUS

Lester J. Whalen, Detroit, Mich., assignor to
 Chrysler Corporation, Highland Park, Mich., a
 corporation of Delaware

Application February 26, 1944, Serial No. 523,983

9 Claims. (Cl. 270—73)

1

This application relates to a bending apparatus. More specifically it relates to an apparatus for folding paper.

At the present time many blueprints are used that are so long that it is difficult to fold them for easy handling. It has been proposed to provide them with so-called accordion folds, which involve one set of similar alternate bends and a second set of alternate bends reversed from the first set of bends. With this arrangement it is possible to open up the blueprint completely or to open up just the desired sections. By the present invention applicant has devised a novel bending or folding apparatus that is well suited to forming accordion folds in blueprints, although the apparatus may be also used for folding of other types and for other materials than blueprints.

Apart from the accordion folding of blueprints, it has been known to fold paper and other materials in many ways, but a drawback with certain schemes has been that, although the folding or creasing operation itself has been easy enough to perform, it has been difficult to make the sections of material at each side of one another keep their fold or even to stay folded to an angle of less than ninety degrees. For example, a blueprint might easily enough undergo accordion folding, but an operator might have to work independently of the machine to make the print stay folded.

An object of the present invention is to provide an improved bending or folding apparatus. More particularly, it is a further object to provide a folding apparatus adapted to form accordion folds in a sheet such as a blueprint.

Another object is the provision of an improved bending or folding apparatus involving rotatable members. Applicant has discovered that by use of an apparatus including rotatable or rotary members a sheet of material may be run continuously through the apparatus, and the bends or folds may be alternately reversed from one another. The rotatable members may take the form of rolls.

Still another object is to associate a machine for folding sheets such as blueprints with a machine for working upon the sheets such as a blueprinting machine. Thus the sheets may run immediately from the sheet-working machine to the sheet-folding machine. It may be desirable to fold some of the sheets coming from the sheet-working machine and not to fold others, while passing the sheets through the sheet-folding machine in both instances.

2

Accordingly it is a still further object of the invention to provide a sheet-folding machine that may be conveniently adjusted between one condition in which it folds sheets and another condition in which sheets pass through it without being folded.

Other objects will appear from the disclosure.

In the drawings,

Fig. 1 is a perspective view showing the novel machine of the present invention;

Fig. 2 is a sectional view taken along the line 2—2 of Fig. 1;

Fig. 3 is a sectional view taken along the line 3—3 of Fig. 1;

15 Figs. 4, 5, and 6 are enlarged sectional views of the structure shown in Fig. 3 in successive stages;

Fig. 7 is a front sectional elevation of a portion of the novel apparatus of the present invention;

20 Fig. 8 is an enlarged sectional view of a portion of the structure shown in Fig. 7;

Fig. 9 is a sectional view taken on the line 9—9 of Fig. 7;

25 Fig. 10 is a diagrammatic view showing the association of the bending apparatus of the present invention with a blueprinting machine; and

Fig. 11 shows diagrammatically rolls embodying a modified form of the invention.

30 Reference character 11 designates the novel bending apparatus of the present invention which, as shown in Fig. 1, includes an upper roll 12 and a lower roll 13. The rolls 12 and 13 are juxtaposed and carry gear segments 14 at opposite ends that mesh with one another so as to cause rotation of one roll in one direction to effect rotation of the other roll in the opposite direction. At opposite ends of the rolls 12 and 13 are positioned uprights 16 and 17 which, as shown in Fig. 7, carry sleeves 18 and 19 for journaling bearings 20 at the ends of the upper roll 12. The lower roll 13 has a bearing 21 at its left end, as viewed in Fig. 7, journalled in a sleeve 22 mounted in an elongated slot 23 in the upright 17. The sleeve 22 has integral therewith, a depending rod 24 which extends along the inner side of the upright 17, and is engaged at its lower end by a cam 25 carried upon a rod 26. The right end of the roll 13, as viewed in Fig. 7, has an elongated bearing 27 journalled in a sleeve 28 positioned in an elongated slot 29 in the upright 16. The sleeve 28 has an integral rod-like extension 30 depending therefrom. The lower end of the extension 30 engages a cam 31

45 formed on the rod 26. The rod 26 is journalled in

sleeves 32 mounted in the uprights 16 and 17. The right end of the rod 26, as viewed in Fig. 7, has an integral crank arm 33 by which the rod 26 may be rocked. In the position of Fig. 7 the sleeves 22 and 28 supporting the bearings 21 and 27 of the lower roll 13 are at the lower end of the slots 23 and 28 so that the rolls 12 and 13 are spaced somewhat from one another but the gears 14 on the rolls are kept in mesh. This is an inoperative position of the rolls. In an operative position the roll 13 is placed near the roll 12, as shown in Fig. 7, and this is accomplished by rocking of the rod 26 by means of the crank arm 33 so that the cams 25 and 31 are brought from the full line position of Fig. 9 shown for the cam 25 to the dash-dot position. This action raises the rod extensions 24 and 30 on the sleeves 22 and 28, thereby raising the lower roll 13 to operative position. The bearing 27 on the lower roll 13 is drivingly connected by a key 34 with a clutch member 35. A mating clutch member 36 is engaged by a driving belt 37. A spring 38 between the clutch members 35 and 36 holds them out of driving engagement, as shown in Fig. 7. A cam 39 is positioned between the clutch member 35 and the upright 16. When the lower roll 13 is raised from the inoperative position of Fig. 7 to an operative position, the clutch member 35 moves upwardly and outwardly against the cam 39 against the action of the spring 38 into engagement with the clutch member 36. Thus when the roll 13 is in lowered inoperative position the clutch members 35 and 36 are disengaged so that there is no driving of the rolls, but when the roll 13 is moved upwardly to operative position the rolls are driven because the clutch members 35 and 36 are forced into engagement with one another.

As shown in Fig. 3, the rolls 12 and 13 may be formed of wood. The bearing members 20 previously referred to as being at the ends of the roll 12 may be an integral part of a rod 40 extending through the roll 12. Similarly the bearing members 21 and 27 at the ends of the roll 13 may be an integral part of a rod 41 extending through the roll 13. A blade-like element 42, which may be of metal, extends almost the entire length of the roll 13, being positioned in an undercut groove 43 and retained therein by wedge-shaped pieces 44. This may be seen more clearly in Fig. 6. As also shown in this figure, the outer portions of the wedges 44 and the portions of the roll 13 immediately adjacent thereto are cut away so as to present concave surfaces 45 at opposite sides of the blade-like element 42. This blade-like element may also be designated as an inserter or as a projection. There is the same arrangement of parts just described on roll 12, namely, a blade-like element 42 or projection, an undercut groove 43, wedge-shaped elements 44, and concave surfaces 45 at opposite sides of the projection 42.

At 180° away from the element 42 there is formed in the roll 12 a recess 46 into which the element 42 of the roll 13 may be inserted as will be hereinafter more fully explained. The recess 46 is formed of walls or side plates 47 and 48. These side plates 47 and 48 along with a block 49 rest in a rather deep recess 50 in the roll 12. The side plates 47 and 48 have, respectively, convex flanges 47a and 48a which overlie the adjacent portions of the roll 12 and the block 49 and provide convex surfaces for a purpose to be described later. The inner edges of the side plates 47 and 48 are loosely pinned to the inner

edge of the block 49 by means of a rivet 51 headed at both ends so that the side plates 47 and 48 and the block 49 are pivotally connected to one another. Fig. 4 shows just a single rivet 51 but it will be understood that there is a series of these rivets since the plates 47 and 48 and the block 49 extend the length of the roll 12. Fig. 4 also shows a coil spring 52 having one end abutting the side plate 47, passing through an opening 53 in the side plate 48, and having the other end abutting the bottom of a recess 54 in the block 49. Fig. 4 also shows a rivet 55 headed at both ends loosely tying the side plate 48 to the block 49 and a spring 56 surrounding the rivet 55 and resting at one end against the plate 48 and at the other end in the bottom of a recess 57 formed in the block 49. As in the case of the rivet 51, it will be understood that there is a plurality of springs 52 and 56 in a plurality of recesses 54 and 57 since the side plates 47 and 48 and the block 49 extend the length of the roll 12. Secured to opposite ends of the block 49 are cams 58 of which only one is shown in Figs. 2, 3, and 4. The cams 58 are pivotally mounted on the roll 12 by means of screws 59 that retain the cams against the ends of the roll 12. The arrangement of the springs 52 and 56 is such that the spring 52 urges the block 49 and the side plate 47 away from one another, and the spring 56 urges the side plate 48 and the block 49 away from one another. The rivet 55 limits the movement of the side plate 48 and the block 49 away from one another. The lower roll 13 has a recess 46 180° away from the blade-like projection 42 on the roll 13. It is formed of similar parts arranged in a similar fashion to the recess 46 in the roll 12. Mounted upon the uprights 16 and 17 is a pair of actuators for the cams 58 in the form of a pair of rollers 60, only the roller mounted upon the upright 16 being shown. The rollers 60 are in position to engage outer curved edges 61 of the cams 58 and thereby to cause the recess 46 in the rolls 12 and 13 to decrease in width. The rolls 12 and 13 are so indexed with respect to one another and are held in this indexed relation by meshing of the gears 14 on the two rolls with one another, that the projection 42 on the roll 13 is adapted to be inserted in the recess 46 of the roll 12, and the projection 42 of the roll 12 is adapted to be inserted in the recess 46 of the roll 13.

At the rear of the machine, as viewed in Fig. 1, there are provided side pieces 61 secured to the uprights 16 and 17. Between the pieces 61 extend a vertical board 62 and a horizontal board 63. There is a space 64 between the boards 62 and 63.

In operation, a sheet of material 65 such as a blueprint is fed through the opening 64 along the board 63 between the rolls 12 and 13. The rolls, as indicated, are sufficiently close to one another to grip the paper and pull it between them as they rotate. Figs. 2 and 3 show the projection 42 of the roll 13 and the recess 46 of the roll 12 approaching the point of tangency of the rolls. In this position the walls 47 and 48 of the recess 46 are spaced from one another and the cams 58 being out of engagement with the roller 60 project somewhat beyond the periphery of the roll 12. As the projection 42 and the recess 46 move nearer the point of tangency, the cams 58 contact the rollers 60 before the projection 42 enters the recess 46. Since contact of the cams 58 with the rollers 60 moves the block 49 toward the plate 47 and under the action of springs

56, the plate 43 toward the plate 41, the space or recess 46 between plates 41 and 43 is closed before entry of the projection 42. Thus the projection 42 of roll 13 inserts a part of sheet 65 into the closed recess 46 between the contacting plates 41 and 43 of roll 12. As the projection 42 forces its own way between the plates 41 and 43, it moves plate 43 away from the plate 41 toward the block 49 against the action of springs 56. In the position of Fig. 5 the projection 42 of roll 13 and the recess 46 of roll 12 are at the tangential portions of the rolls 12 and 13; and the projection 42 has entered the recess 46 as far as it can. In the position of Fig. 6, the projection 42 and the recess 46 have moved out of the point of tangency of the rolls, and the projection has withdrawn from the recess. The cams 58 are still in contact with the rollers 60, as indicated, and the wall 43 is thus urged back toward the wall 47 under the action of the springs 52 so that the regions of the paper adjacent the bend 67 are pressed against one another. Thereafter the cams 58 move out of contact with the rollers 60, and the wall 43 and the block 49 move away from the wall 47 under the action of the springs 52, thus opening up the recess 46 so that the part 66 of the sheet 65 moves out of the recess. It will be noted that in the position of Fig. 5, in which the projection 42 is within the recess 46, the convex flanges 47^a and 48^a on the plates 41 and 43 press regions 69 of the sheet 65 immediately adjacent the portion 66 within the concave portions 45 of the roll 13 at the sides of the projection 42. This action prevents the formation of secondary bends at the regions 69.

After the portion 66 and the bend 67 of the sheet 65 leaves the recess 46 in the roll 12, continued rotation of the rolls causes the sheet to be fed therebetween until after 180° of movement from engagement of the projection 42 of the roll 13 with the recess 46 of the roll 12, the projection 42 of the roll 12 engages the projection 46 of the roll 13 in the manner previously referred to. This causes the formation of a second bend 67 in the sheet 65 similar to the first bend except that it is reversed in direction. This process is continued and so the sheet is provided with a series of alternately reversed bends, as indicated in Fig. 1. A platform 69 supports the sheet 65 as it comes from the rolls, with bends or creases formed therein alternately reversed so that the sheet is piled up in accordion style.

As previously stated the sheet 65 may be a blueprint and the apparatus 11 may be placed adjacent a blueprint machine 70 so that as the blueprint leaves the machine 70 it passes directly to the apparatus 11. The bending apparatus 11 may be driven from the blueprint machine 70 by engagement of the belt 37 with a pulley 71 connected to the blueprint machine. As previously stated, the belt 37 drives the apparatus 11 through the clutch parts 35 and 36. The portion 66 of the sheet 65 inserted by the projection 42 in the recess 46 provides a sudden take-up of the sheet 65. Compensation is had for this by driving the apparatus 11 at a slower rate than the machine 70 or by providing an initial slack in the sheet 65 of sufficient magnitude that it may be taken up gradually throughout the entire passage of the sheet through the rolls 12 and 13. It will be appreciated that the blueprints to be folded by the apparatus 11 are generally of considerable length so that folding of the accordion type is desirable. At certain times

blueprints of rather short lengths may come from the blueprint machine 70 and for convenience these prints are also passed through the apparatus 11. If they are short enough in length to require folding of the type performed by the apparatus 11, the rod 26 is rocked sufficiently to move the cams 25 from the dash-dot position of Fig. 9, to the full line position of that figure. This action causes the lower roll 13 to be lowered from the upper roll 12, as indicated in Fig. 7, and the downward movement of the clutch 35 with respect to the cam 39, allows the clutch part 35 to be shifted sufficiently for disengagement from the clutch part 36. Thus rotation of the rolls 12 and 13 is stopped. The blueprints are now passed through the space between the rolls 12 and 13 and since the rolls are not rotated, blueprints are not folded. The gears 14 interconnected with the rolls 12 and 13 stay in mesh, as indicated in Fig. 7, so that there is no disturbance of the relative angular positions of the rolls 12 and 13 that permits entry of the projections 42 within the recess 46. When finally the blueprints coming from the blueprint apparatus 70, are again to be folded, the rod 26 is rocked to move the cams 25 back to their original position and the roll 13 is moved upwardly to the roll 12 and the clutch part 35 is re-engaged with the clutch part 36.

A very important feature of the present invention is the fact that after each bend in the sheet is formed, the portions immediately adjacent the bend are pressed against one another so that the resultant bend or crease is effective to relate the sections of the sheet between the bends in such a fashion that the sheet piles easily in the accordion fashion shown in Fig. 1. As will be observed from this figure, the relative angle of the sections between the bends is considerably less than the right angle. If the portions adjacent the bend were not pressed against one another after the formation of the bend, the relative angle between the sections might well be greater than the right angle, in which case the sheet would not pile as indicated. The method by which this is accomplished is shown and has been described with reference to Figs. 5 and 6.

Rolls 12 and 13 each have one recess 46 and one projection 42. Obviously the rolls may have more projections and recesses. Rolls 72 and 73 of Fig. 11, for example, each have two projections 42 and two recesses 46. This may be varied as desired.

The drawings show rolls 12 and 13 and rolls 72 and 73, but other types of rotatable members may be employed in their stead.

The intention is to limit the invention only within the scope of the appended claims.

I claim:

1. Apparatus for providing a bend in a sheet, comprising a pair of rotatable members, one having a projection and the other having a recess formed of a first wall and a second wall, a member on the outer side of the first wall, means loosely tying the member to the first wall and causing the first wall to move away from the second wall after a predetermined movement of the member away from the walls, a first resilient means acting between the second wall and the member to urge the member away from the second wall, a second resilient means acting between the first wall and the member to urge the first wall away from the member toward the second wall, means for applying force to move,

against the action of the first resilient means, the member toward the walls and therewith under the action of the second resilient means, the first wall toward the projection and the second wall, means for rotating the rotatable members to feed the sheet between them and to cause the projection to pry apart the walls and to introduce a part of the sheet between the walls for forming the bend in the said part of the sheet, means for withdrawing the projection from the walls of the recess thereby to permit the first wall under the action of the second resilient means and the member to move back toward the second wall for pressing the portions of the sheet adjacent the bend against one another, and means for causing the force applied to the member to be removed and therewith to cause the first resilient means to move the member and with it the first wall under the action of the tying means away from the second wall for releasing the said part of the sheet from the recess.

2. Apparatus for providing a bend in a sheet, comprising a pair of rotatable members, one having a projection and the other having a recess formed of a first wall and a second wall, a member on the outer side of the first wall, a rivet headed at both ends loosely tying the member to the first wall and causing the first wall to move away from the second wall after a predetermined movement of the member away from the walls, a first spring surrounding the rivet and seated in a recess in the member at the side toward the first wall and acting between the bottom of the recess and the first wall to urge the first wall away from the member toward the second wall, a second spring seated in a recess in the member and passing through the first wall into contact with the second wall and acting between the second wall and the bottom of the recess to urge the member away from the second wall, means for applying force to move, against the action of the second spring, the member toward the walls and therewith under the action of the first spring, the first wall toward the projection and the second wall, means for rotating the rotatable members to feed the sheet between them and to cause the projection to pry apart the walls and to introduce a part of the sheet between the walls of the recess for forming the bend in the said part of the sheet, means for withdrawing the projection from the walls of the recess thereby to permit the first wall under the action of the first spring and the member to move back toward the second wall for pressing the portions of the sheet adjacent the bend against one another, and means for causing the force applied to the member to be removed and therewith to cause the second spring to move the member and with it the first wall under the action of the tying means away from the second wall for releasing the said part of the sheet from the recess.

3. Apparatus for providing a bend in a sheet, comprising a pair of juxtaposed rotatable members, one having a recess and the other having a projection, means for rotating the rotatable members to feed the sheet between the rotatable members and to cause the projection to insert a part of the sheet in the recess for forming the bend in the said part of the sheet, means for simultaneously increasing the spacing of the rotatable members and stopping the rotation thereof to cause the sheet to be passed between the rotatable members freely without feeding engagement, and means interconnecting the rotatable members for causing rotation of one rotatable member in one direction to rotate the

other rotatable member in the opposite direction, said means being effective upon increasing the spacing of the rotatable members as aforesaid to maintain the interconnection of the rotatable members for causing the projection and the recess to interengage properly upon return of the rotatable members to feeding position.

4. The apparatus specified in claim 3, the means interconnecting the rotatable members comprising a pair of gears meshing with one another and having teeth of sufficient length to maintain mesh of the gears upon increasing of the spacing between the rotatable members for assuring reengagement of the projection and the recess upon return of the rotatable members to feeding position.

5. Apparatus for providing in a sheet a first bend and a second bend reversed from the first bend, comprising a pair of juxtaposed rolls each having a projection and a recess formed of a pair of spaced walls, a first adjusting means for causing the spacing of the walls of the recess in the said other roll to decrease, means for rotating the rolls to feed the sheet between them and to cause the projection of the said one roll to pry apart the walls of the recess in the said other roll and to introduce therein a part of the sheet for forming the first bend in the said part of the sheet, the said roll-rotating means causing the projection of the said one roll to withdraw from the recess in the said other roll whereupon the first wall-adjusting means again decreases the spacing of the walls of the recess in the said other roll to press the portions of the sheet adjacent the first bend against one another and then increases the wall spacing to release the said first bend from the said other roll, a second adjusting means for causing the spacing of the walls of the recess in the said one roll to decrease, the said roll-rotating means causing the projection of the said other roll to pry apart the walls of the recess of the said one roll and to introduce therein another part of the sheet for forming the second bend in the said other part of the sheet, the said roll-rotating means causing the projection of the said other roll to withdraw from the recess as the said one roll whereupon the second wall-adjusting means again decreases the spacing of the walls of the recess in the said one roll to press the portions of the sheet adjacent the second bend against one another and increase the wall spacing to release the said second bend from the said one roll, means for simultaneously increasing the spacing of the rolls and stopping the rotation thereof to cause the sheet to be passed between the rolls freely without feeding engagement, and means interconnecting the rolls for causing rotation of one roll in one direction to rotate the other roll in the opposite direction, said means being effective upon increasing the spacing of the rolls as aforesaid to maintain the interconnection of the rolls for causing the projection and the recess to interengage properly upon return of the rolls to feeding position.

6. Apparatus for providing a bend in a sheet, comprising a pair of juxtaposed rotatable members, one rotatable member having a projection and the other rotatable member having a recess formed of walls movable toward and away from

one another, the rotatable members being so indexed with respect to one another as to cause the projection to enter and to withdraw from the recess during rotation of the members, means for rotating the rotatable members to feed the sheet between them and for causing the entry of the projection in the recess to insert a part of the sheet in the recess to form the bend in the said part, and means for causing the walls of the recess to be moved into contact with one another before entry of the projection in the recess for causing the insertion of the sheet in the recess to force apart the walls thereof for insuring a more satisfactory bend in the sheet.

7. Apparatus for providing a bend in a sheet comprising a pair of juxtaposed rotatable members, one rotatable member having a projection and the other rotatable member having a recess formed of walls movable toward and away from one another, the rotatable members being so indexed with respect to one another as to cause the projection to enter and to withdraw from the recess during rotation of the members, and means for rotating the rotatable members to feed the sheet between them and for causing the entry of the projection in the recess to insert a part of the sheet in the recess to form the bend in the said part, the spacing of the walls of the recess on entry of the projection therein being less than the thickness of the projection for causing insertion of the sheet and the projection in the recess to force apart the walls thereof thereby insuring a more satisfactory bend in the sheet.

8. Apparatus for providing a bend in a sheet, comprising a pair of juxtaposed rotatable members, one rotatable member having a projection and the other rotatable member having a recess formed of walls movable toward and away from one another, the rotatable members being so indexed with respect to one another as to cause the projection to enter and to withdraw from the recess during rotation of the members, means for rotating the rotatable members to feed the sheet between them and for causing the entry of

the projection in the recess to insert a part of the sheet in the recess to form the bend in said part, means for causing the walls of the recess to be moved into contact with one another before entry of the projection in the recess for causing the insertion of the sheet in the recess to force apart the walls thereof for insuring a more satisfactory bend in the sheet, and means for causing the last mentioned means to function after withdrawal of the projection from the recess for pressing the portions of the sheet adjacent the bend against one another.

9. Apparatus for providing a bend in a sheet, comprising a pair of juxtaposed rotatable members, one rotatable member having a projection and the other rotatable member having a recess formed of walls movable toward and away from one another, the rotatable members being so indexed with respect to one another as to cause the projection to enter and to withdraw from the recess during rotation of the members, means for rotating the rotatable members to feed the sheet between them and for causing the entry of the projection in the recess to insert a part of the sheet in the recess to form the bend in the said part, resilient means for urging the walls apart, a follower, a cam resiliently connected with one wall and rotatable with the rotatable member having the recess so as to engage the follower before entry of the projection in the recess for resiliently urging the said one wall toward the other wall before entry of the projection in the recess and to become disengaged from the follower a short time after withdrawal of the projection from the recess, whereby the projection inserts a part of the sheet in the recess while forcing the walls of the recess apart for insuring an improved bend in the sheet and after withdrawal of the projection the walls of the recess move back toward one another to press the portions of the said part of the sheet adjacent the bend against one another and a short time later move apart to release the said part of the sheet.

LESTER J. WHALEN.
